UNITED STATES PATENT OFFICE.

JOHN O. DAVISON, OF MEMPHIS, TENNESSEE.

CONCRETE BUILDING CONSTRUCTION.

1,141,445.

Specification of Letters Patent.

Patented June 1, 1915.

Application filed July 10, 1914. Serial No. 850,227.

To all whom it may concern:

Be it known that I, JOHN O. DAVISON, a citizen of the United States, residing at Memphis, in the county of Shelby and State of Tennessee, have invented new and useful Improvements in Concrete Building Construction, of which the following is a specification.

The invention relates to building construction, and more particularly to the class of concrete building construction, which is an improvement over the subject matter of an application filed by me on or about the 10th day of January 1914, and bearing Serial No. 811,457.

The primary object of the invention is the provision of a concrete building construction wherein the window casements and doors are made from concrete and fit in the wall of the building, which wall has its sections interlocked with the parts of the door or window casement, thus rendering the device strong, durable and less liable to conflagrations.

Another object of the invention is the provision of a structure of this character wherein the sections of the wall can be interlocked for the joining thereof, thereby enabling the convenient erection of the building without material expense, use of nails or fasteners, and the requirement of skilled labor.

A further object of the invention is the provision of a structure of this character wherein the completed building is rendered damp-proof, practically fire-proof, and airtight.

Other objects will be in part obvious and in part hereinafter pointed out.

The invention accordingly consists in the construction, combination of elements and arrangement of parts which will be exemplified in the construction hereinafter set forth, and the scope of the application of which will be indicated in the following claim.

In the drawings:—Figure 1 is a fragmentary front elevation of a building constructed in accordance with the invention, showing the window casement therein. Fig. 2 is a sectional view on the line 2—2 of Fig. 1. Fig. 3 is a sectional view on the line 3—3 of Fig. 1. Fig. 4 is a perspective view of a column for use in the house or in constructing a porch. Fig. 5 is a transverse sectional view therethrough. Fig. 6 is a perspective

view of the sill of the window casement. Fig. 7 is a perspective view of the head of the window casement. Fig. 8 is a perspective view of one of the side or stile sections thereof.

Similar reference characters indicate corresponding parts throughout the several views in the drawings.

Referring to the drawings in detail, A 65 designates the outer slabs, B the inner slabs of the vertical wall of a building, while C the outer corner slabs, and D the inner corner slabs are employed at the juncture or meeting of right angular walls of a building.

E designates the window casement, and F the porch column, the same, together with the slabs hereinbefore mentioned, will be hereinafter fully described.

The slabs A and B are each formed with substantially L-shaped outer locking flanges 11 and an intermediate substantially T-shaped locking flange 12, while arranged between the outer and inner slabs A and B is 80 a substantially H-shaped securing or locking member 13, each being adapted to interlock with the said flanges 11 and 12 of superimposed inner and outer slabs A and B for joining the same in producing the vertical 85 wall 10.

The outer and inner corner slabs C and D are formed with substantially L-shaped locking flanges 14, and substantially T-shaped locking grooves 15, with which are 90 adapted to engage the locking members 13, one vertical series of the said members 13 adjacent to the corner slabs C and D each being formed with a substantially T-shaped locking extension 16 which is adapted to interlock with the vertical series adjacent thereto of the members 13. In erecting the vertical wall 10 the outer and inner slabs A and B are arranged in rows parallel with each other, and the members 13 are positioned therebetween so that the flanges 11 and 12 will lock with the same, thus joining the said slabs to form a unitary structure.

In the building of the wall 10 the next row of slabs A and B are arranged in staggered 100 relation to the previously laid slabs and are joined together by the members 13, as before set forth. At the corner of the right angular walls the corner slabs C and D are united together as shown in the drawings, and the 110 members 13 arranged at the corner in vertical series are joined to the extensions 16 of

the vertical series of members 13 adjacent thereto.

The window casement comprises a sill section 17, vertical stile sections 18 and a head section 19, the sill sections being cut away at 20 to accommodate the lower ends of the stile sections 18 which are supported thereon. All of the sections of the window casement E are formed with inner facing extensions 21, while the sill section 17 and the head section 19 are formed with outer facing extensions 22, these extensions being disposed outside of the plane of the outer and inner slabs A and B respectively. The head section 19 is formed with slots 23 in which are journaled pulleys 24 over which are trained the sash cords, which together with the sashes are not shown. The inner surfaces of the stile sections 18 and the head section 19 are formed with grooves 25 in which are inserted the parting strips 26 of the ordinary well-known construction for the guiding of the window sashes in the opening and closing thereof.

25 The slabs A, B, C and D, the window casement E, and the porch column F, together with the locking members 13, are each made from concrete, while the parting strips 26 in the window casement are made

30 from wood.

The vertical stile sections 18 of the window casement E are formed on their outer faces with substantially T-shaped locking members 27 which are adapted to interlock with the flanges 14 of adjacent inner and outer slabs A and B for the fastening of the

window casing within the wall 10 of the building.

In Figs. 4 and 5 there is shown a porch column which comprises the face slabs 28 formed with locking flanges 29 which engage the locking ribs 30 of a substantially X-shaped core 31 which fits centrally within the column for uniting the face slabs. The column is built up in an identical manner 45 as the wall 10 of the building, and is used in the constructing of a porch therefor.

From the foregoing it is thought that the construction of my device will be clearly understood, and therefore a more extended explanation has been omitted.

What is claimed is:—

In a building construction, a sectional wall, a casement comprising a base sill having cut-away portions in opposite ends 55 thereof, vertical stiles engaged in the notches, a head piece supported by the stiles, locking flanges formed on the stiles, flanges formed on the sections of the wall for locking engagement with the first-named flanges, 60 the said vertical stiles and head piece being formed with grooves in their inner faces, parting strips inserted within the grooves, and facing extensions formed on the sill stiles and head piece.

In testimony whereof I affix my signature in presence of two witnesses.

JOHN O. DAVISON.
